UNITED STATES PATENT OFFICE.

PAUL SCHMIDT, OF VIENNA, AUSTRIA-HUNGARY, ASSIGNOR TO THE FIRM OF ELECTR. ISOLIR-UND INSTALLATIONSARTIKELERZEUGUNG, INGRE. SCHOTT & SCHILDORFER, OF VIENNA, AUSTRIA-HUNGARY.

APPARATUS FOR COVERING CABLES, RODS, TUBES, AND THE LIKE.

No. 840,715.

Specification of Letters Patent.

Patented Jan. 8, 1907.

Application filed February 9, 1905. Serial No. 244,894.

To all whom it may concern:

Be it known that I, PAUL SCHMIDT, a subject of the Emperor of Austria-Hungary, residing at Vienna, Austria-Hungary, have invented certain new and useful Improvements in Apparatus for Covering Cables, Rods, Tubes, and the Like, of which the following is a specification.

This invention relates to that kind of apparatus for winding bands and the like onto cables, rods, or tubes, heretofore employed, in which the bobbins carrying the bands, &c., to be wound onto the cable are rotatably arranged in fixed bearings, while the cable or other object to be covered is rotated and is at the same time advanced longitudinally. This arrangement has the advantage that the bands, &c., can be led through a liquid material for impregnating the same and rendering them adhesive.

The present invention relates to means employed in connection with such apparatus whereby the rotation of the cable, &c., and the longitudinal advance thereof are effected simultaneously without requiring any further auxiliary device. For this purpose there is provided a frame rotatable round the longitudinal axis of the cable or other object, which frame carries rollers that can be pressed toward each other and are thereby made to grip the cable between them so as to effect its rotation round its longitudinal axis as they revolve with the frame, while worm-gearing, in connection with the rollers and engaged with a stationary worm-wheel or toothed wheel arranged outside the revolving frame, effects the rotation of the rollers on their axes, whereby the cable, &c., to be covered has an advancing motion imparted to it simultaneously with the rotary motion imparted by the frame.

In order to afford a better grip on the cable, endless bands of suitable material are stretched over each pair of rollers, which bands are formed with longitudinal grooves that fit accurately round the circumference of the cable. In place of the endless bands the rollers may be provided with grooved peripheries.

I shall describe the said invention with reference to the accompanying drawings, in which—

Figures 1, 2, and 3 show, respectively, a

longitudinal section, a sectional plan, and cross-section on line A B, Fig. 1, of one arrangement. Fig. 4 shows a partial longitudinal section of a modified construction; Fig. 5, an end view of the actuating-gear, while Figs. 6 and 7 show views of other arrangements of the actuating-gear. Figs. 8 to 11 show diagrammatic views of different arrangements for effecting the longitudinal motion of the cable, &c.

The frame *a*, Figs. 1, 2, and 3, has at its ends tubular journals *b* and *c*, rotatably mounted in fixed bearings *d*, so that the entire frame can be rotated by means of the toothed wheel *e*, suitably driven. In the frame *a* are mounted the rollers *g* and *g'*, serving to rotate and move forward the cable *f*. In order to insure a reliable grip of the rollers upon the cable which is to be covered by the bands *f'*, there are stretched over the rollers endless bands *h*, made of suitable flexible material, such as caoutchouc, leather, or woven fabric, and formed with grooves *i*, which fit accurately round the periphery of the cable. In place of a flexible band a suitably-formed endless grooved chain may be employed. The rollers *g* are rotatably mounted upon axes *j*, that are carried by the frame *a*. Each of the two rollers *g* has a lateral rectangular projection on which is fitted a spiral wheel *k*, which is engaged with a stationary annular spiral gear *l*, suitably supported outside the frame *a*.

The axes *j'* of the rollers *g'* do not extend through the frame *a*, but are carried in longitudinal slots in the frames *m*, which are pivotally mounted on the axes *j*.

To the axes *j'* are connected looped pieces *n*, to which are fixed screws having nuts, by turning which the rollers *g'* can be shifted so as to stretch the bands *h*.

For enabling the rollers *g'* to be pressed toward each other screws *o* are provided on the frame *a* by means of nuts on which bearing on the frames *m* the pressure exercised by the roller upon the cable can be regulated.

On rotating the frame *a*, together with the above-described parts carried thereby, by means of the toothed wheel *e*, the cable *f* will be carried round with it. As the worm-wheels *k* are engaged with the fixed annular worm *l* the rollers *g* are at the same time rotated upon their axes, whereby the cable *f*

will at the same time be advanced longitudinally.

In the arrangement shown in Figs. 4 and 5 the worm-wheels k are engaged with spirally formed teeth on a ring p , fixed to the face of one of the bearings d .

In the arrangement shown in Fig. 6 a worm and worm-wheel gear is employed, wherein the worm-wheels k are engaged with worms q , rotatably mounted on the frame a and rotated by toothed pinions r , gearing with a fixed toothed ring s .

In the arrangement shown in Fig. 7 the toothed pinion r , fixed to the worm q , is engaged with an internally-toothed ring s' .

Fig. 8 shows diagrammatically the arrangement of a double set of endless bands h , passing over corresponding sets of gripping rollers.

Fig. 9 shows an arrangement in which one endless band of each set is replaced by a single grooved roller t .

In the arrangement at Fig. 10 grooved

rollers t alone are employed, while Fig. 11 shows an arrangement of two grooved rollers t in combination with one endless band h .

I claim—

In an apparatus for covering cables, rods, tubes and the like, the combination with a rotatable frame, of rollers adapted to revolve therewith and to rotate around their individual axes, endless bands placed over said rollers and formed with grooves adapted to grip the article to be covered, and means arranged independently of said frame, adapted to rotate the said rollers while revolving with the frame around their axes, thereby rotating the cable and simultaneously advancing the same.

In testimony whereof I have hereunto set my hand in presence of two subscribing witnesses.

PAUL SCHMIDT.
